CLAIM

The ornamental design for a starlit tree, as shown and described.

DESCRIPTION

FIG. 1 is a perspective view of a starlit tree, showing my new design.

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The even broken lines in the figure drawing views represent unclaimed environment structure of the starlit tree only and form no part of the claimed design.
